Nelson Howard

UNITED STATES PATENT OFFICE

FREDERIC E. BERTRAND, OF LYNN, MASSACHUSETTS, ASSIGNOR TO UNITED SHOE MACHINERY CORPORATION, OF PATERSON, NEW JERSEY, A CORPORATION OF NEW JERSEY

SHOE AND HEEL DRILLING MACHINE

Application filed January 11, 1928. Serial No. 245,966.

This invention relates to drilling machines and particularly to drilling machines of the type employed to drill through the heel seat of a shoe into a heel which has been applied 5 to the shoe.

A machine of the type referred to is described and claimed in my copending application Serial No. 54,046, filed Sept. 2, 1925, and the present invention is in the nature of 10 a development of and improvement upon that machine.

Machines of this kind are provided with a drill which is adapted to be fed manually downward through a previously formed 15 guide hole in a last upon which the shoe is mounted, and to drill through the heel seat of the shoe, and into the heel, a hole for the reception of a screw fastener which is later to be inserted and tightened for the purpose 20 of clamping and holding the last, shoe and heel tightly together. It is essential that the fastener receiving hole be drilled deeply enough into the heel to permit the fastener to be screwed far enough into the heel to 25 hold the latter securely, and it is equally important that the hole shall not be deep enough to weaken the heel materially or approach too closely to any of the surfaces of the heel.

30 Inasmuch as the drill enters the work at the bottom of a deep guide hole in the last and the place on the work where the hole is to be drilled is entirely concealed from view, it is impossible to determine by inspection 35 how the drilling of the hole is progressing and the use of any depth gage dependent upon co-operation with the work makes it necessary for the operator to rely upon his sense of touch to determine when the hole 40 is finished. Since lasts are not uniform in height, the use of any gaging means co-operating with the last is liable to result in inaccuracy and the production of non-uniform holes. It will, therefore, be realized 45 that there is a problem of substantial difficulty presented.

It is with the solution of this problem that the present invention is concerned, and the object of the invention is to provide, in a 50 shoe and heel drilling machine, improved

means for positively and definitely determining the point to which the hole shall be drilled in the work.

In the illustrated embodiment of the invention the point to which the hole is drilled 55 is determined by an adjustable stop cooperating with an extensible shaft by which the drill is rotated and an important feature of the invention resides in improved means for facilitating adjustment of the point in the 60 work at which the feeding movement of the drill shall be stopped. In the illustrated machine the stop is connected to a rack which, in turn, is geared to an indicator bearing indicia to aid in determining the adjustment and co-operating with locking means 65 which operates positively to preserve the setting to which the stop is adjusted.

Still another feature of the invention resides in the provision upon the indicator of 70 one or more additional indicia relating to the depth of the hole to be drilled and usable to determine the correct adjustment of the drill in a holder in which it is secured and through which movement is imparted to it. 75

The foregoing and other features and advantages of the invention will be better understood and appreciated by reading the following detailed description of one embodiment thereof in connection with the accompanying drawings, in which,

Fig. 1 is a view in side elevation, partly in section, of a structure embodying the invention;

Fig. 2 is a view of the same in front elevation; and

Fig. 3 is a face view of the indicator upon an enlarged scale.

Referring now to the drawings, 10 indicates the housing which encloses the gearing and supports the pendent drill shaft in a machine of the type disclosed in my prior application, hereinbefore mentioned.

The drill shaft, which is extensible vertically to permit the drill to be fed into the work, comprises two telescoping sections 12 and 14, a universal joint 16, a shaft section 18, and a chuck 20 having a set screw 22 to secure the drill 24. The shaft section 18 is surrounded by a handle 26 adapted to be 100

grasped by the operator, who manipulates the drill to feed it into and withdraw it from the work. The two telescoping sections 12 and 14 of the drill shaft are joined by a key and slot connection 28, by virtue of which rotation of the shaft section 12 is always transmitted to the section 14, although the latter is freely movable longitudinally of the section 12.

10 The surface of the tread plate of a work support, upon which a lasted shoe 30 and heel 32 are sustained, is indicated at 34. This work support is normally stationary and the drill, which is rotated continuously, is inserted 15 through a guide hole in the last 36 which is in the shoe and fed downward through the heel seat of the shoe into the heel, as shown in Fig. 1.

In order accurately to determine the depth 20 to which the drill 24 shall penetrate the heel there is provided a rigid stop 38 surrounding the movable drill shaft section 14 and through which the said shaft section is freely slideable. The shaft section 14 is provided at its upper 25 end with a collar 40 adapted to engage the stop 38, to limit positively and definitely the downward movement of this section of the drill shaft and, consequently, of the drill.

The stop 38 is secured to the lower end of 30 a rack bar 42 which is adjustable vertically in a stationary guide 44. The upper portion of the rack bar 42 is provided with teeth 46 which mesh with a pinion 48 mounted upon a shaft 51 to the outer end of which is secured 35 a dial indicator 52. It will be apparent that rotation of the indicator 52 will cause the stop 38 to be adjusted up or down and, in order to secure the stop immovably in the desired position of adjustment, the periphery of 40 the indicator 52 is provided with notches 54 adapted to co-operate with a stationary pin 50 to lock the indicator against rotation. The shaft 51 is slideable longitudinally through a sufficient distance to permit the indicator to be 45 disengaged from the pin 50 when it is desired to change the adjustment and a spring 58 surrounding the indicator shaft serves to move the indicator dial into engagement with the pin 50 when the adjustment is accomplished.

The indicator 52 is provided with two groups of notches and two corresponding groups of indicia. One of these groups of indicia relates to the thickness of the work 55 to be operated upon. In the illustrated apparatus this group of indicia consists of the numbers from 8 to 20, inclusive, which relate to the various heights of heels in which holes are to be drilled. Since it is customary to 60 designate the height of a heel in eighths of an inch the notches 54 of this group are so spaced as to correspond to eighths of an inch of movement of the stop 38 and the indicator 52 is so adjusted that the pin 50 engages in 65 the notch which is marked for the height of

the heel to be operated upon. For example, as shown in Figs. 2 and 3, the indicator is set at 16, this setting being correct for a 16/8, or two-inch, heel. It will be apparent from an inspection of the drawings that the higher 70 the heel the higher the position to which the stop 38 will be adjusted, which is consistent with the requirement that holes be drilled to the same depth in all heels.

The second group of notches in the periphery of the indicator, one of which is indicated by the reference numeral 60, has associated with it a second group of indicia each consisting of the letter S followed by a fraction which defines the fraction of an inch in depth 75 to which the hole in the heel is to be drilled. The utility of the indicia in this group is in adjusting the drill 24 in its chuck 20, the process being to set the indicator 52 so that the notch S $\frac{1}{2}$, for example, is engaged by the 80 pin 50, if it is desired to drill a hole one-half inch deep, and then, with the collar 40 resting upon the stop 38, the drill is so adjusted in its chuck that the point of the drill rests upon the surface of the work support 34, after 85 which the set screw 22 is tightened. The drill will now drill a hole one-half inch deep in any heel placed upon the work support provided the indicator 52 is set in accordance with the height of that particular heel. 90

In the ordinary use of the apparatus the drill will be set in the chuck to drill into the work to a depth of, say, one-half or five-eighths of an inch and left that way indefinitely, the only change in adjustment that 100 is required thereafter being when a change occurs in the height of the heels being operated upon.

Having thus described my invention, what I claim as new and desire to secure by Letters 105 Patent of the United States is:—

1. In a shoe and heel drilling machine, the combination of a rotating drill carrier which is manually movable to feed a drill into the work, a rigid, adjustable stop adapted to be 110 engaged by an element of said carrier to limit the feeding movement, an indicator bearing indicia relating to the thickness of the work for which the stop is to be adjusted, and positive movement transmitting connections between the indicator and the stop. 115

2. In a shoe and heel drilling machine, the combination of a rotating drill carrier which is manually movable to feed a drill into the work, a rigid, adjustable stop adapted to be 120 engaged by an element of said carrier to limit the feeding movement, an indicator bearing indicia relating to the thickness of the work for which the stop is to be adjusted, positive movement transmitting connections between 125 the indicator and the stop, and means for locking the indicator in adjusted position.

3. In a shoe and heel drilling machine, the combination of a rotating drill carrier which is manually movable to feed a drill into the 130

work, a rigid, adjustable stop adapted to be engaged by an element of said carrier to limit the feeding movement, an indicator bearing indicia relating to the thickness of the work for which the stop is to be adjusted, and gearing connecting the indicator and the stop.

4. In a shoe and heel drilling machine, the combination of a work support, a rotating drill holder vertically movable toward and from the work support, a drill adjustably secured in the holder, a movable stop for adjustably determining the limit of movement of the drill holder toward the work support, an indicator connected to the stop, indicia on the indicator relating to the thickness of the work to be drilled, and another indicium on the indicator relating to the depth of the hole to be drilled, said indicium being usable to determine the proper adjustment of the drill in the holder.

20 In testimony whereof I have signed my name to this specification.

FREDERIC E. BERTRAND.
